UNITED STATES PATENT OFFICE.

JOHN LEWIS MILTON, OF CLEVELAND, OHIO, ASSIGNOR TO THE TEAGLE COMPANY, OF CLEVELAND, OHIO, A CORPORATION OF OHIO.

COIL-CASE AND TERMINAL.

1,275,170.

Specification of Letters Patent.

Patented Aug. 6, 1918.

Application filed August 17, 1917. Serial No. 186,742.

To all whom it may concern:

Be it known that I, JOHN L. MILTON, a citizen of the United States, residing at Cleveland, in the county of Cuyahoga and State of Ohio, have invented certain new and useful Improvements in Coil-Cases and Terminals, of which the following is a specification, reference being had therein to the accompanying drawing.

10 This invention relates to a case for coils or other electrical devices, and to an improved terminal with which the case is fitted.

The object of the invention is to provide a case of this character with a terminal fitting which is at once efficient, durable, producible at a low cost, and adapted to be readily secured to the wall of the case.

In the accompanying drawings, which illustrate a preferred embodiment of the invention—

Figure 1 is a front elevation of a case fitted with four of the improved terminals.

Fig. 2 is a plan view of the said case, a portion of the structure being broken away to illustrate the interior construction and arrangement.

Fig. 3 is an enlarged fragmentary section on the line 3—3 of Fig. 1.

30 Fig. 4 is an enlarged fragmentary section on the line 4—4 of Fig. 1.

Fig. 5 is an enlarged detail of a part of the terminal structure.

Referring in detail to the construction illustrated, 1 is a bottom member of the case, it being made preferably of metal, and in the construction shown it is merged with a base structure (largely broken away) by which the case is supported. 2 is the tubular side wall of the case which is preferably formed of non-conducting material, a highly compressed and waterproofed paper fiber having been found satisfactory. The upper end of the case is closed by a cover 3 which may be stamped from metal and secured in any desired manner, as by screws 4.

The case illustrated is made to receive two coils 5, 5, and a condenser 6, the said coils and condenser being adapted for use as a part of the ignition system of a two-cylinder internal combustion engine. To the side wall of the case are secured two pairs of terminal fittings designated as entireties by 7 and 8. Each pair of the terminals serves 55 one of the coils 5, which has its leads 9 and

10 running to the terminals 7 and 8 respectively.

The terminal fittings are alike in construction, and a description of one will suffice for all. The terminals are of the binding post sort and each comprises a screw-threaded stem or post 11 which is carried by a base 12. The base is preferably stamped from sheet metal and the stem is rigidly secured to it by riveting, the base being perforated 60 to receive the stem, as indicated in Figs. 3 and 5. For purposes of economy I prefer to form the stem of a suitable quality of screw steel and the base 12 of brass. The said base is formed with prongs 12^a which 70 are adapted to be bent at right-angles to the base so as to pass through the side wall of the case.

To receive each of the terminals the side wall of the case has a hole 13 and a pair of 75 holes 14 punched therein, the hole 13 being adapted to receive the stem 11, while the holes 14 receive the bent prongs 12^a of the base 12, said prongs being bent over and clenched down, as indicated in Fig. 3. 80

The stem 11 and base 12 should be united and applied to the side wall of the case in such a manner that a flat face of the base is rigidly clamped against either the inner or outer face of the side wall 2. I prefer the 85 construction illustrated in which the base is disposed against the inner face of the side wall.

When the assembled stem and base have been attached to the side wall, as indicated 90 in Fig. 3, the corresponding lead from the adjacent coil, as lead 10, is passed through one of the holes 14 and having preferably been given one or more turns around the stem 11, has its end electrically connected, as 95 by soldering, at 15 to one of the prongs 12^a.

The ends of the prongs 12^a, the end part of the lead 10, and the holes 14 are covered by a soft rubber washer 16 which surrounds the stem 11 and is pressed against the side wall 100 of the case by a molded terminal fitting 17. This fitting may be formed of any suitable non-conducting material such, for example, as bakelite, and has a main part 17^a and a branch part 17^b which are respectively perforated to receive the stem 11, and an electrical conductor 18. The molded fitting 17 is formed with a shoulder 17^c to receive a washer 19, and the end of the conductor 18 is clamped between this washer 19 and a nut 110

20, the screwing home of the nut 20 serving to simultaneously compress the rubber washer 16 and to tightly clamp the end of the conductor 18.

5 In assembling the electrical devices illustrated the coils and condenser are inserted in the case and, the coils having been suitably interconnected with the condenser and the leads 9 and 10 permanently attached to the 10 terminals, the parts are permanently secured and sustained by filling the space surrounding the coils and condenser by suitable insulation 21 which is poured in a hot and semi-liquid state and then hardens on cooling. The 15 cover 3 can then be secured in position and the other parts of the terminal fittings applied.

It will be obvious to one familiar with the art in question that while the materials 20 which I employ in the production of my improved case and terminal fittings are inexpensive and the construction simple and capable of production at small labor cost, a structure is secured which is strong and 25 durable and adapted to effectively perform its intended functions. In particular, the method of attaching the base of the binding post to the wall of the case, I have found to be especially satisfactory, both as to low- 30 ness of cost and permanence.

Furthermore, while the base of the binding post is made of brass and can, therefore, readily be electrically connected by soldering with the leads 9 or 10, the construction 35 permits the use of another and cheaper material for the stem part of the terminal. Again, the soft rubber washer 16, by reason of its resilience, not only serves to protect the molded fitting 17 from injury, but also 40 acts to effectively cover the prongs 12^a of the base member, the electrical connection at 15, and the apertures 14 in the wall of the case.

What I claim is:—

45 1. In a structure of the character described, the combination of a case having a wall of non-conducting material, and a binding post terminal comprising a metallic member having a stem part and a base part, 50 the said base part being formed with integral prongs which extend through and grip the wall of the case.

2. In a structure of the character described, the combination of a case having a 55 non-conducting wall formed with apertures, and a binding post terminal comprising a metallic member having a stem part and a base part which is formed with integral prongs, the base part of the said metallic 60 member being arranged on the inside of the case wall with the stem part extending through one of the wall apertures and the base prongs extending through other of said apertures and gripping the wall.

65 3. In apparatus of the character de-

scribed, the combination of a case having a wall of non-conducting material, an electrical device therein, a binding post terminal comprising a metallic member having a stem part of ferrous metal and a base part 70 of brass, the said base part being formed with integral prongs which extend through and grip the wall of the case, and a lead from the electrical device electrically connected to the base part of the said metallic 75 member.

4. In apparatus of the character described, the combination of a case having an apertured wall of non-conducting material, an electrical device in the case, a binding 80 post terminal comprising a metallic member having a stem part and a base part which is formed with integral prongs, the said base part being arranged against one face of the case wall with the prongs extending through the wall apertures and gripping the wall, and a lead from the electrical device extending through one of the wall apertures and electrically connected to the metallic member outside the case. 85

5. In apparatus of the character described, the combination of a case having an apertured wall of non-conducting material, an electrical device in the case, a binding 90 post terminal comprising a metallic member having a stem part and a base part which is formed with integral prongs, the said base part being arranged against the inner face of the case wall with the stem part extending outward through a wall aperture and the base prongs extending through other wall apertures and tightly gripping the wall, and a lead from the electrical device extending through one of the 95 prong apertures of the wall and electrically connected to one of the base prongs outside the case. 100

6. In a structure of the character described, the combination of a case having an apertured wall of non-conducting material, 110 a binding post terminal comprising a metallic member having a screw-threaded stem part and a base part which is formed with integral prongs, the stem part extending through one of the wall apertures and 115 the base prongs extending through other apertures and gripping the wall, a resilient washer arranged on the stem next to the wall to cover the prong apertures therein, and a metallic washer and nut on the stem 120 to clamp an electric conductor, the said resilient washer being pressed against the wall when the nut is tightened. 125

7. In a structure of the character described, the combination of a case having an apertured wall of non-conducting material, a binding post terminal comprising a metallic member having a screw-threaded stem part and a base part which is formed with integral prongs, the stem part extend- 130

ing through one of the wall apertures and the base prongs extending through other apertures and gripping the wall, a resilient washer arranged on the stem next to the wall 5 to cover the prong apertures therein, a molded insulating block aperture to pass over the threaded stem and to receive an electrical conductor, a metallic washer on the stem en-

gaging a shoulder on the said block, and a nut on the stem adapted to clamp the said 10 conductor against the metallic washer and simultaneously compress the resilient washer against the wall of the case.

In testimony whereof, I hereunto affix my signature.

JOHN LEWIS MILTON.
